TREMOLO DEVICE FOR ACCORDIONS

Walter Gerber, Bern-Bümpliz, Switzerland

Application December 18, 1945, Serial No. 635,680
In Switzerland January 6, 1945

7 Claims. (Cl. 84—376)

1

This invention relates to accordions and is specifically directed to means incorporated therein which are adapted to shake the tones produced by these instruments.

It is an object of the invention to provide in an accordion, preferably on its so-called melody side, between the bellows and the sounding section an intermediate partition having at least one aperture wherein is disposed a vibrator member which is adapted to be swung about its normal position or position of rest by the flow of air passing through said aperture, whereby the tones produced by means of said accordion will be shaken by the action of said swinging vibrator member.

Another object of the invention is to provide in said partition a second aperture for the additional flow of air and a movable member in cooperation with said aperture for controlling the flow of air therethrough, said member being adapted to close said aperture.

A further object of the invention is to provide means for immobilizing said vibrator member as long as said second aperture is open, so that the tones produced will not be shaken.

Still another object of the invention is to provide operating means in operable connection with said immobilizing means and said movable member for manipulating the same accordingly from outside in order to produce ordinary tones or shaken tones.

These and other objects and features of the invention will appear from the following detailed description of one specific embodiment thereof illustrated in the accompanying drawing, in which:

Fig. 1 is a sectional elevation of a portion of the keyboard of an accordion showing the vibrator device in operable position.

Fig. 2 is a sectional elevation similar to Fig. 1, however showing the vibrator device in immobilized position.

Fig. 3 is a side elevation of the intermediate partition located between the bellows and the sounding section of the accordion.

Referring more particularly to the drawing, numeral 1 represents a portion of the bellows of the accordion and numeral 5 the reed chest with key-board and mechanical section on the so-called melody side of the accordion. The bellows 1 and the reed chest 5 are separated by an intermediate partition 2 having two apertures 3 and 4 for the flow of air passing therethrough into or out of the bellows 1. The aperture 4 is oblong and there is disposed therein a leaf spring 7 hav-

2

ing substantially the shape of the aperture 4. One end of the leaf spring 7 is fixed on the frame 8 of the aperture 4 by means of screws 8a and the other free end carries a metal plate 6. The leaf spring 7 with the metal plate 6 constitutes the vibrator and in its normal position closes the aperture 4 leaving but only a very slight space therebetween which allows the unhampered pendulous swinging movements of the vibrator about its normal position across aperture 4.

On the sounding or mechanical side of the partition 2 cooperates a flap 9 with the other aperture 3, which flap is secured to two arms of a hinge pin 10 which is mounted for rotation on the partition 2. The hinge pin 10 has bent one end 12 at right angle for being turnable by means of a manipulating device which will be described hereinafter. Two coil springs 11—11a are arranged on the hinge pin 10 and act upon the two arms 9a—9b of the same so as to close the flap 9. An arm 13 of the hinge pin 10 extends towards the leaf spring 7 and carries a damper 14 which will be firmly applied against the leaf spring 7; when the flap 9 is moved into opened position, whereby the damper 14 urges the vibrator 6—7 beyond the normal position approximately into open position shown in Fig. 2 and prevents the vibrator 6—7 from swinging. When the flap 9 is closed, the damper 14 is lifted off the leaf spring 7 and moved out of range of its vibration as shown in Fig. 1 so that the vibrator can freely swing.

The lever end 12 of the hinge pin 10 can be moved against the action of the coil springs 11 by means of the rod 15 and the levers 16 and 18 the latter of which is rotatable about a fulcrum 17. The manipulating end of the lever 18 carries a knob 20a which penetrates through a predetermined slot 20 to the outside of the reed chest 5. In the upper end position of the knob 20a in the slot 20, as shown in Fig. 1, the flap 9 is closed and the vibrator can freely swing under the flow of air passing through the aperture 4. In the lower end position of the knob in the slot 20 the lever 18 urges the lever 16 and the rod 15 against the action of the coil springs 11—11a to the left, whereby the flap 9 is opened and the damper 14 is applied against the leaf spring 7 to immobilize the vibrator, as shown in Fig. 2. Therefore, it is possible to play the accordion without actuation of the vibrator.

When, while playing the accordion, only one or two keys on the key-board are pressed down, particularly such keys which produce tones of a high pitch, the flow of air through the sounding unit 26 would be insufficient to amply actuate the vi-

brator. In order to supply a supplemental flow of air, there are provided two small holes 24 in the sounding board 25 and a flap 23 mounted on a lever 22 pivotal at 21 for closing said holes 24. This lever 22 is subjected to the closing action of a spring 27 and extends with the lever arm remote from the flap 23 into the range of a nose 28 provided on the operating rod 15. When the rod 15 is moved to the right, while the flap 9 is closed and the damper 14 lifted off the vibrator, the nose 28 simultaneously moves the lever 22 and flap 23 into opening position.

It is to be understood that a desired frequency of the vibrator involves a predetermined weight of the metal plate 6 or/and a predetermined thickness of the leaf spring 7. The space between the sounding section 26 and the normal position of the vibrator plate 6 must be sufficient to allow the vibrator to swing freely.

It is obvious that various changes and modifications may be made to the details of construction without departing from the general spirit of the invention as set forth in the appended claims.

Having thus described the invention, what is claimed as new and desired to be secured by Letters Patent, is:

1. In an accordion on the melody side thereof, an intermediate partition located between the bellows and the sounding section, two apertures in said partition for the flow of air therethrough, a vibrator comprising a metal plate mounted on a leaf spring which is disposed in one of said apertures, said metal plate being predetermined in weight and said leaf spring being predetermined in thickness by the desirable frequency of said vibrator, a movable flap for controlling the air flow through the other aperture, operating means in operative connection with said flap and said vibrator for opening said flap and simultaneously immobilizing said vibrator from outside, and resilient means tending to close said flap and simultaneously supersede the immobilization of said vibrator.

2. In an accordion, a partition disposed between the bellows and the sounding section and having at least one aperture for the flow of air therethrough, and a vibrator member arranged in operative position within said aperture and adapted to vibrate about said operative position by the flow of air passing through said aperture, and damping means disposed for contact with said vibrator member and adapted to retain the latter in inoperative position at a location beyond said aperture.

3. In an accordion equipped with a bellows and a reed chest having a partition therebetween, said partition being provided with an elongated aperture, and a resilient vibrator member mounted on said partition and adapted in operative position to lie within said aperture and to pendulously oscillate through said aperture with a predetermined frequency, when air is caused to pass through said aperture in the direction from said bellows to said reed chest or vice versa.

4. In an accordion having a bellows and a reed chest; a partition arranged between said bellows and said reed chest and having two apertures, first and second, respectively, a resilient vibratory member mounted with one of its ends on said partition, the opposite end of said member extending in normal and operative position within said first aperture and being adapted to pendulously oscillate in said operative position across said first aperture with a predetermined fre-

quency when air is caused to pass through said first aperture in either direction thereof, a movable member placed over said second aperture to open and close the same, respectively, stop means connected with said movable member and adapted to immobilize said vibratory member when said movable member is in open position, and means operatively connected with said movable member and extending to a location without said accordion to permit simultaneous operation of said movable member and of said stop means.

5. In an accordion according to claim 4, in which said stop means is normally spaced from said vibratory member and in open position of said movable member engages said vibratory member to displace the latter beyond said first aperture.

6. In an accordion having a bellows and a reed chest; a partition arranged between said bellows and said reed chest and provided with two apertures, first and second, respectively, said first aperture being of elongated form, an elongated vibratory member resiliently mounted with one of its ends on said partition, the remainder of said vibratory member extending to said first aperture and being substantially in registry therewith in operative position of said vibratory member, said vibratory member pendulously oscillating through said first aperture with a predetermined frequency when air is caused to pass through said first aperture in either direction thereof, a first flap mounted for swinging movement on said partition for opening and closing said second aperture, stop means connected with said first flap and extending toward said vibratory member for engagement therewith when said first flap is in open position, rod means in operative connection with said first flap and said stop means and extending to a location outside of said accordion whereby simultaneous operation of said first flap and said stop means may be achieved, a passageway for air passing through said partition, and a second flap for opening and closing said passageway upon operation of said rod means, said second flap being operatively connected to said rod means whereby said passageway is opened in closed position of said first flap in order to permit air flow of sufficient strength toward said vibratory member for obtaining the tremolo effect thereof.

7. In an accordion according to claim 6, wherein said vibratory member comprises a leaf spring and a metal plate secured to one end of said spring, the opposite end of said spring being mounted on said partition, whereby said one end carrying said metal plate is positioned substantially in said first aperture, said metal plate being predetermined in weight and said leaf spring being predetermined as to its spring action to produce a predetermined frequency of oscillation of said vibratory member.
